C. A. BUNKER

CAN CAPPING MACHINE

Filed Feb. 2, 1925

40 INVENTOR
Charles A. Bunker
Arthur L. Brown ATTORNEY

UNITED STATES PATENT OFFICE.

CHARLES A. BUNKER, OF KANSAS CITY, MISSOURI, ASSIGNOR TO H. P. COMSTOCK, OF KANSAS CITY, MISSOURI.

CAN-CAPPING MACHINE.

Application filed February 2, 1925. Serial No. 6,214.

This invention relates to can capping machines and it is especially designed to apply caps to the necks or delivery spouts of cans.

The invention contemplates a capping device capable of moving a cam lever carried by the cap into locking position, the application of the cap and the locking of the lever being done by a single operation of the capping device and the invention consists in certain novel 10 parts and combinations of parts, all of which will be specifically described hereinafter, reference being had to the accompanying drawings, in which

Fig. 1 is a perspective view of a can capping device constructed in accordance with 15 my invention.

Fig. 2 is an elevational view of the can capping device with the front plate removed.

Fig. 3 is a vertical cross sectional view 20 through the device.

Fig. 4 is a detailed perspective view of one of the caps to be applied, showing the lever in unlocked position.

Fig. 5 is a like view showing the cap applied 25 to the neck of the can with the lever in locked position, and

Fig. 6 is a fragmentary view of a can to which the cap is to be applied.

The can 1 may be of the usual construction 30 with a neck or delivery port 2. The neck is provided with a circumferential rib or flange 3 and an annular groove 4, the latter for engagement by the depending flange 5 of the cap 6. The depending flange is slotted and it 35 is provided with a bead 7 to engage the groove 4 as is well understood. The cap is also provided with a locking lever 8. All of the structure thus far described is old in the prior art so no claim is made for either the can or the 40 cap, the invention residing only in the tool for applying the cap to the can.

The mechanism for applying the cap consists of a back plate 10 and a front plate 11 secured together by bolts 12 and 13. The plates 45 10 and 11 are in spaced relation and between them is located a vertical slide comprising the plate 14 having a slot 15 near its upper end and a slot 16 near its lower end. The slots receive guide rollers 17 and 18 between the plates so that the slide must move in a rectilinear direction. Between the plates 10 and 11 are pivoted actuating levers 19 and 20 movable about the pivots 21 and 22 and they are 50 connected to the upper end of the slide 14 by

links 23 and 24, pivoted to the slide at 25. 55 The slide has notches 26 and 27 near its lower end which receive the rollers 28 and 29 on the ends of the elbow levers 30 and 31, the elbow levers being pivoted between the plates at 32 and 33. The outer ends of the elbow levers 60 are connected to capping jaw arms 34 and 35 which are provided with elongated arcuate slots 36 and 37 near their lower ends and ride on the rollers 38 and 39 between the plates 10 and 11. 65

The lower ends of the arms 34 and 35 carry jaws 40 and 41 which are adapted to engage under the flange 3 when the tool is applied as will be described hereinafter. The two plates 10 and 11 are connected at their lower ends by 70 a cross bar 42 which carries an inverted U-shaped positioning member 43 having depending fingers spaced apart, a distance substantially equal to the diameter of the cap 6 so that the cap can be received and positioned 75 between the arms when the tool is applying it to the neck 2 of the can 1.

The cross bar 42 has an end 44 which projects laterally a sufficient distance so that it will overlap the top of the cap 6 (see Fig. 80 3). The purpose of the projecting portion 44 is to prevent the tool from being applied so that the lever 8 will come on the back side of the tool. If it did, the lever would hit against the projection 44 and the operator 85 would know that the tool was not properly positioned. With this tool, it is necessary that the cam lever 8 come on the front side of the tool, because the front side of the tool carries a mechanism applying lever 90 which must register with the cam lever 8 in order to swing it into locking position when the cap is applied.

The lever positioning mechanism is shown 95 as comprising a plate 45 at right angles to the plate 11 and it is fastened to the plate 11 by riveting it at 46 and 47. The plate 45 is an outstanding vertically disposed flat plate with cam slots 48 and 49 and on the respective sides of the plate 45 are two locking lever applying arms 50 and 51. 100

The levers 50 and 51 have bearing fingers 52 and 53 which engage in a slot 64 in the slide 14 and they are connected one to the other by the bolts 54, 55 and 56. The bolts 105 carry rollers or spacers 57, 58 and 59. The spacers 57 and 58 ride in the slots 48 and 49. The spacer 59 is located between the two cam

ends 60 and 61 of the arms 50 and 51. It is these cams 60 and 61 which throw the locking cam lever 8 from the position shown in Fig. 4 to the position shown in Fig. 5.

5 When it is desired to apply the cap, the cap is introduced between the depending fingers of the member 43. The tool is then placed over the neck of the can so that the jaws 40 and 41 engage under the bead or 10 flange 3 with the cam portion 60 and 61 back of the locking lever 8 of the cap. Then the levers 19 and 20 are spread apart so that they pull down on the slide 14. The downward movement of the slide 14 rocks the 15 elbow levers 30 and 31 so that there would be a tendency to raise the arms 34 and 35, but since the jaws 40 and 41 are under the bead 3, due to the fact that the elbow levers 30 and 31 swing the upper ends outward, the 20 plates must move downward and since the plates carry the bar 42 with the cap received in the member 43, it will be obvious that the cap will be forced down over the neck 2 of the can.

25 At the same time that the cap is forced into position the slide 14 is moving downwardly at a speed in excess of the downward speed of the two plates 10 and 11. Consequently it carries the two levers 50 and 51 downwardly and since their rollers 57 and 58 ride in the cam slots 48 and 49 the two levers 50 and 51 will have a down movement and a rocking movement, that is they will rock on their projections 52 and 53 causing the 30 ends 60 and 61 to move outwardly and downwardly and then inwardly and downwardly so that the lever 8 will be swung into locking position as shown in Fig. 5. The cap is now applied. The levers 19 and 20 may then 35 be swung up to the position shown in Figs. 2 and 3 to release the cap. A new cap may now be inserted and the cycle of operations just described, will be repeated on a new canning operation.

40 45 From the foregoing it will be seen that the cap can be quickly and efficiently applied to the can and that the tool may be expeditiously released to receive another cap, and that the can capping operation will be greatly facilitated by the use of my invention.

What I claim and desire to secure by Letters-Patent is:—

1. A can capping device comprising a pair 55 of pivoted jaw arms, said arms having arcuate slots therein, jaws carried by the arms, supporting means for the arms, engaging said slots, a slide, means connecting the arms to the slide to actuate them into and out of can neck engaging position and a cap receiving means carried by the support.
2. A can capping device comprising a pair 60 of pivoted jaw arms having longitudinally extending elongated slots therein, jaws carried by the arms, supporting means for the

arms, engaging said slots, a slide, means connecting the arms to the slide to actuate them into and out of can neck engaging position and a cap receiving means carried by the support. 70

3. A can capping device comprising supporting means, levers carried by the supporting means, a longitudinally movable slide carried by the supporting means, links connecting the levers to the slide, pivoted arms carried by the supporting means, actuating members pivoted to the supporting means and operatively engaging the arms and the slide, jaw members carried by the arms and cap receiving means carried by the supporting means. 75

4. A can capping device comprising supporting means, levers carried by the supporting means, a longitudinally movable slide carried by the supporting means, links connecting the levers to the slide, pivoted arms carried by the supporting means, actuating members pivoted to the supporting means and operatively engaging the arms and the slide, jaw members carried by the arms and cap receiving means carried by the supporting means, a guide plate carried by the supporting means and a cap-locking lever actuating means carried by the slide and co-operating with the guide plate whereby the locking lever actuating means will be moved so that its lower end has first an outwardly and downwardly and then an inwardly directed movement when the slide is operated. 85

5. A cam capping machine comprising two parallel plates constituting supporting means, a longitudinally movable slide between the plates, operating means, links connecting the operating means to the slide, jaw members pivoted between the plates, links operatively connecting the jaw members to the slide, a cap receiving means carried by the plates, a plate on one of the first named plates extending at right angles thereto and having cam slots and a lever loosely mounted in the slide and having means engaging the cam shaped slots so that when the slide is moved in one direction the lever will have motion imparted to it in an outward and downward direction. 100

6. A can capping machine comprising two parallel plates, a longitudinally movable slide between the plates, means for imparting movement to the slide, pivoted jaw members carried by the plates, means for operatively connecting the jaw members to the slide, a can cap receiving means carried by the plates, a can cap locking lever actuating means connected to the slide and a guide plate carried by one of the first named plates for controlling the movement of the last named means. 105

7. A can cap applying device comprising a frame, a longitudinally movable member slidably mounted in said frame, means movable toward each other to engage with the neck of the can, a can cap receiving means, means connecting the neck engaging means with the 115 120 125 130

slidable member and a can cap locking lever actuator operatively connected with the slideable member.

8. A can cap fastening device comprising a frame, a longitudinally movable plate carried by the frame, means carried by the frame and movable towards each other to engage with the neck of a can, means for holding a

cap to be applied to the neck of a can, and means including a cam carried by the frame 10 for moving a can cap lever into locking position, said lever-moving means including a member connected with the plate and actuated by the cam.

In testimony whereof I affix my signature.
CHARLES A. BUNKER.
